(57) **CLAIM**

The ornamental design for a camera tray with dual handle grips, as shown and described.

DESCRIPTION

FIG. 1 is a perspective view of a camera tray with dual handle grips showing my new design;

FIG. 2 is a front view thereof;

FIG. 3 is a back view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a perspective view of the camera tray with dual handle grips shown in an alternative configuration.

The broken lines in the drawings are shown to illustrate portions of the camera tray with dual handle grip and form no part of the claimed design.
